ERNST FELDMANN, OF ROCKFORD, ILLINOIS, ASSIGNOR TO THE INGERSOLL MILLING MACHINE CO., OF ROCKFORD, ILLINOIS, A CORPORATION OF ILLINOIS.

MILLING-MACHINE SPINDLE-SADDLE.

1,143,373.

Specification of Letters Patent. Patented June 15, 1915.

Application filed June 8, 1914. Serial No. 843,876.

To all whom it may concern:

Be it known that I, ERNST FELDMANN, a citizen of Germany, residing at Rockford, in the county of Winnebago and State of Illinois, have invented certain new and useful Improvements in Milling-Machine Spindle-Saddles, of which the following is a specification.

This invention relates in general to milling machines and has more particular reference to the saddle and the spindle-supporting and driving mechanism of what is commonly termed a face plate milling machine.

In order to insure smooth and perfect work and to prevent vibration and chattering of the tools it is essential in machines of this character that the tool-spindle be mounted and held with the utmost rigidity.

With this end in view one of the primary objects of my invention is the provision of novel means for mounting the spindle so that it can be adjusted longitudinally to suit the requirements of the work and which will hold the spindle rigidly and inflexibly in working position.

Another object is the provision of improved driving means which will drive the spindle at the tool end, thereby obviating any vibration or irregularity in the operation of the tool which might result from torsional strains on the spindle if it were driven from the end opposite to that on which the tool is mounted.

A further object is the provision of means for rigidly and unyieldingly connecting the projecting ends of the spindle sleeve and pinion shaft sleeve so that vibration of the sleeves will be obviated and so that the sleeves will move together as a unitary structure during their longitudinal adjusting movements.

A still further object is the provision of simple and efficient means for locking the spindle and pinion shaft against longitudinal movement after they have been adjusted to the required position.

Other objects and many of the attendant advantages of this invention will be apparent as the same becomes better understood by reference to the following description when considered in connection with the accompanying drawings.

Referring to the drawings—Figure 1 is a side elevation of a spindle saddle embody-

ing my invention; Fig. 2 is a longitudinal sectional view taken on the line 2—2 of Fig. 1; Fig. 3 is an end elevation looking toward the left in Fig. 1; Figs. 4 and 5 are sectional views taken on the lines 4—4 and 5—5 of Fig. 1; Fig. 6 is a plan view of the construction shown in Fig. 1; Fig. 7 is an end elevation looking toward the right in Figs. 1 and 6, a portion of the casing being broken away to show the underlying gears; Fig. 8 is a sectional view on the line 8—8 of Fig. 6, and Fig. 9 is a transverse sectional view on the line 9—9 of Fig. 1.

Referring to the drawings, reference character 11 designates a portion of the main frame of the milling machine which is formed to provide a track or guideway upon which the spindle saddle 12 may be adjusted. The saddle may be retained in adjusted position by any suitable holding means, one practical form being illustrated in the drawings as comprising overlying lips 13 carried by the saddle and adapted to be clamped against an opposed face of the main frame guideway by means of 80 clamping bolts 14.

While the guideway is illustrated on the drawings as being vertically disposed so that the tool carrying spindle in the saddle is arranged horizontally it will be manifest 85 that the track may be horizontal and the spindle disposed vertically without departing from the essence of my present invention.

The spindle saddle 12 is cored longitudinally to provide a pair of parallel bores 15 and 16 in which the tool spindle 17 and the pinion shaft 18 are mounted in a manner to be later described.

Within the bore 15 is snugly fitted the 95 spindle sleeve 19 which is capable of longitudinal adjustment within the bore but has a machined contact fit so that vibration of the sleeve in the saddle is precluded.

The spindle 17 is journaled in the sleeve 19 and a bushing 21 is interposed between the spindle and the sleeve, the end of the bushing being flanged radially over the end of the sleeve as shown in Fig. 8, and the sleeve having an annular shoulder 22 against 105 which the inner end of bushing 21 abuts.

A second bushing 23 is disposed within the contracted portion of the sleeve 19 around the spindle 17, and a lock nut 24 threaded onto the spindle at the inner end 110

of the sleeve serves to prevent outward movement of the spindle with respect to the sleeve, suitable washers or bearing rings 25 being interposed between the lock nut 24 and an annular shoulder 26 formed at the inner end of the sleeve.

The outer end of the spindle is equipped with a gear wheel 27 which may be rigidly secured to the spindle in any approved manner, the gear being shown in the present instance as formed integral with the spindle. It will be manifest that the inner face of the gear 27 together with the lock nut 24 precludes longitudinal movement of the 15 spindle with respect to the sleeve.

In order to obviate any lateral movement of the spindle the saddle is formed at the rear of the bore 15 with a supplemental bearing 28, preferably equipped with a suitable bushing 29 in which the spindle rotates, and is capable of longitudinal adjustment.

The outer face of the gear 27 forms the face plate to which the cutting tool is attached, this face being preferably provided 25 with suitably tapped sockets 31 into which the tool fastening bolts are threaded. The present machine is primarily designed for very heavy work in which face plate tools are employed, but it will be manifest that 30 smaller tools may be used if desired by mounting the tool in the centrally disposed socket 32 of the spindle.

Instead of driving the spindle from its inner end, as has been the practice to a large 35 extent heretofore, I contemplate the provision of driving mechanism including a pinion which will mesh with the gear 27 at the tool end of the spindle. This manner of driving obviates torsional strains on the tool 40 spindle, thereby eliminating the tendency of the spindle to chatter in its bearings, which causes rough and uneven work. The spindle is, in the present instance, therefore driven from a pinion 33 constructed integral 45 with or fixedly attached to the outer end of the pinion shaft 18 rotatably mounted in a sleeve 34 fitted into the bore 18, suitable bushings 35 being preferably interposed between the shaft and the surrounding 50 sleeve. Longitudinal movement of the shaft relatively to the sleeve 34 is prevented by the inner face of the pinion 33 and a lock nut 36 pinned, or otherwise fixed, upon the shaft at the inner end of the sleeve. The spindle 55 shaft is driven from the main drive shaft 37 through a pair of intermeshing beveled gears 38 and 39, the gear 39 having a splined connection with the spindle shaft to permit longitudinal adjustment of said shaft, and 60 the gear 38 being splined on the shaft 37 to permit adjustment of the saddle on the main frame without disturbing the driving connection between the drive shaft 37 and the gear.

65 From Fig. 4 it will be observed that the

gear 38 has an elongated body which is rotatably mounted in a sleeve 41 fixed in a bore 42 formed in the saddle normal to the bores 15 and 16, the gear being held against longitudinal movement relatively to the 70 sleeve by an inner annular shoulder 43 and a lock nut 44 disposed at opposite ends of the sleeve, suitable bushings 45 and washers 46 being employed to take up the wear.

For the purpose of adjusting the spindle 75 longitudinally to suit the requirements of the work I have equipped one face of the sleeve 19 with rack teeth 46 (Figs. 2, 8 and 9) and have mounted in the saddle an adjusting spindle or shaft 47 equipped at its 80 inner end with a pinion 48 which meshes with the rack. The outer end of the spindle 47 is squared, as indicated at 49, to receive the handle or operating lever by means of which the shaft 47 may be rotated to longitudinally adjust the tool spindle. It should be understood that I do not desire to limit my invention to this particular means of adjustment since other mechanisms for moving the sleeve 19 longitudinally will readily suggest themselves to those skilled in the art.

Since the sleeves 19 and 34, in which the tool spindle 17 and the pinion shaft 18 are respectively mounted, project outwardly some little distance beyond the face of the saddle it will be obvious that when the tool is doing very heavy work the enormous lateral pressure exerted upon the tool will tend to spring and distort the sleeve 19. For the purpose of backing up the sleeve and overcoming any tendency of the same to yield or distort under heavy work and also for the purpose of holding the pinion 33 in proper driving engagement with the gear 27 and, furthermore, to insure the simultaneous and 100 unitary longitudinal movement of both sleeves 19 and 34 when longitudinal adjustment of the spindle is required, I have rigidly connected the extremities of the sleeves 19 and 34 by means of a heavy substantial member 51 snugly fitted upon the ends of the sleeves and preferably formed in the shape of a housing, as shown, to surround the peripheries of the intermeshing 105 pinion and gear.

While the housing 51 is machined to a drive fit upon the sleeves 19 and 34 nevertheless, I prefer to employ an auxiliary fastening means which will insure a rigid and unyielding connection between the 110 sleeves, and with this end in view I have tapped the housing and each sleeve to receive the set-screws 52 and 53, as shown in Figs. 8 and 1 respectively. It will thus be manifest that this housing serves to cover the rear face and the periphery of the pinion and gear 27 so as to protect the operator against possible injury as well as serving as a rigid and inflexible connection between the 115 ends of the sleeves which will absolutely pre-

clude relative movement between the sleeves either laterally or longitudinally.

In order to protect the operative against becoming entangled in the pinion or gear wheel from the outer face I prefer to employ an outer plate 54 which completely covers the end of the pinion and also the gear teeth on gear 27, the gear 27 being provided with a peripheral groove 55 to receive the plate 54 which lies back of the face of the gear on which the cutting tool is mounted. The gear is thereby wholly inclosed while the outer face of the gear 27, usually termed the face plate, is left exposed for the attachment of the tool.

For the purpose of providing a simple, cheap and efficient means for locking the spindles 19 and 34 in any position to which they may have been adjusted longitudinally I have provided the saddle 12 with intersecting longitudinal and transverse slots 56 and 57 formed in one wall of the bore 15 so as to provide a yielding portion 58 of the wall which may be tightly clamped about the sleeve 19 by means of clamping bolts 59. Similarly the wall of the bore 16 is provided with intersecting longitudinal and transverse slots 61 and 62 respectively, forming the yielding portion 63 which may be clamped around the sleeve 34 to lock the same in adjusted position by means of the clamping bolts 64. When it is desirable to adjust the spindle longitudinally the bolts 59 and 64 are loosened so as to permit the required longitudinal adjustment of the sleeves 19 and 34 to be made, whereupon these bolts are again tightened up to securely and fixedly clamp the sleeves in the position to which they have been adjusted. It will be obvious that since the spindle sleeve and the pinion shaft sleeve are rigidly connected together by the housing 51 it is only necessary to provide adjusting mechanism for one of these sleeves, any adjusting movement of one sleeve being transmitted to the other through the housing.

It will be understood from the foregoing that I have provided a saddle in which the tool spindle is firmly and unyieldingly mounted, in which the spindle is driven at the tool end so that all torsional strains upon the spindle are obviated, that the spindle and pinion shaft are rigidly connected, thereby precluding vibration or chattering of the spindle and insuring equal longitudinal movements of both members when adjustment is required, that the spindle driving gear is completely inclosed in protected casing, and that a simple but highly efficient means for locking the spindle in adjusted position is provided in the body of the saddle itself.

While I have shown and described a preferred embodiment of the invention I do not desire to limit myself to the specific embodi-

ment shown since various changes in the structural details may be resorted to within the scope of appended claims without departing from the spirit of the invention or sacrificing any of its material advantages.

I claim:

1. In a milling machine the combination of a saddle, a plurality of sleeves mounted axially movable therein with their corresponding ends projecting beyond the end of the saddle, a spindle and a pinion shaft journaled respectively in said sleeves, a driving connection between said spindle and shaft, and means for rigidly connecting the projecting ends of said sleeves.

2. In a milling machine the combination of a saddle, a plurality of sleeves mounted therein and projecting beyond the end of the saddle, a spindle journaled in one of said sleeves, a pinion shaft journaled in the other sleeve, a driving connection between said spindle and shaft, means rigidly connecting the projecting ends of said sleeves, and means for adjusting said sleeves longitudinally in the saddle.

3. In a milling machine the combination of a saddle, a pair of sleeves longitudinally adjustable in said saddle, one end of each sleeve projecting beyond the end of the saddle, a pinion shaft and a spindle journaled respectively in said sleeves, means whereby the projecting ends of said sleeves are rigidly connected together, and intermeshing gears carried by the outer ends of said pinion shaft and said spindle whereby the spindle is driven from said shaft.

4. In a milling machine, the combination of a saddle, a pair of longitudinally adjustable sleeves mounted in said saddle, a pinion shaft journaled in one of said sleeves and provided at its outer extremity with a pinion, a spindle journaled in the other sleeve and provided at its outer extremity with a gear-wheel meshing with said pinion, and a housing disposed over said pinion and said gear, said housing being fixedly secured to each of said sleeves whereby the sleeves are rigidly connected together.

5. In a milling machine, the combination of a saddle, a spindle sleeve carried thereby with one end projecting outside the saddle, a pinion sleeve also carried by the saddle and having one end projecting outside the saddle, a pinion shaft journaled in said pinion sleeve, a spindle journaled in said spindle sleeve, driving means at the outer ends of said spindle and pinion shaft whereby the spindle is driven from the pinion shaft, means whereby the outer ends of said sleeves are rigidly connected together, and means for adjusting said sleeves together longitudinally in the saddle.

6. In a milling machine, the combination of a saddle, a pair of sleeves longitudinally adjustable in said saddle, a spindle jour-

naled in one of said sleeves, means for preventing longitudinal movement of the spindle relatively to the sleeve, a pinion shaft journaled in the other sleeve, means for preventing longitudinal movement of said pinion shaft relatively to said sleeve, intermeshing gears carried by the outer ends of said shaft and spindle whereby the spindle is driven from said shaft, and a housing 10 closing said gears, said housing being rigidly attached to each of said sleeves whereby said sleeves are rigidly connected together at their outer ends.

7. In a milling machine, the combination 15 of a saddle, a pair of sleeves slidably mounted in parallel relation in said saddle with their ends projecting beyond the saddle, a spindle journaled in one of said sleeves and provided at its outer end with a gear wheel, 20 a pinion shaft journaled in the other sleeve and provided at its outer end with a pinion meshing with said gear wheel, means for rigidly connecting the outer ends of said sleeves together, means for simultaneously 25 adjusting said sleeves longitudinally in the saddle, means for preventing longitudinal

movement of the shaft and spindle relatively to the sleeves, and driving mechanism splined to said pinion shaft through which power is applied to said spindle.

30

8. In a milling machine, the combination of a saddle provided with a plurality of bores, a sleeve slidably disposed in each of said bores, means for adjusting said sleeves longitudinally of the bores, the walls of said bores being slotted to provide yielding clamping portions, and means for clamping said yielding portions around the sleeves to lock the sleeves in adjusted position.

35

9. In a milling machine, the combination 40 of a saddle, a plurality of sleeves mounted axially movable therein with their corresponding ends projecting beyond the saddle, a member rotatably mounted in each sleeve, a driving connection between said rotary members, and means rigidly connecting said 45 projecting ends of the sleeves.

ERNST FELDMANN.
